DOOR LOCK

James Hillgren, Huntington Park, Calif.

Application June 29, 1940, Serial No. 343,191

11 Claims. (Cl. 70—150)

My present invention relates to locks, particularly building door locks.

One of the principal objects of this invention is to provide a latch bolt mechanism having a minimum number of operating and other parts, and also one which is easily assembled in a one-piece housing and held together by a single pin.

Another important object of this invention is to provide a latch bolt mechanism having a single spring, and one of substantial size, for ejecting the bolt and returning the operating member to an inoperative position.

An important object of this invention also is to provide an actuating spring and associated elements for a latch bolt mechanism in which the operating spindle or other member is required to be operated or moved a small amount only to retract the latch member or bolt, and in which only slight resistance is offered to the inward movement or retraction of the latch member or bolt, relative to the force required to operate the spindle or operating member.

An important object of this invention is to provide a novel and simple spindle construction for operating the latch member or bolt, and also to provide novel and simple means of securing the spindle in the knobs, or other operating members, and further novel and simple means of non-rotatively securing the spindle within the knobs or other operating members.

An important feature of this invention is to provide a novel and simple means of locking a latch member or bolt in a locking position, and also novel means of operating the same.

One of the objects of this invention is to provide novel and simple means of assembling the operating or locking elements in the knobs.

A still further important object of this invention is to provide a simple lock of this class for locking the door when in one room, but in which the lock may be unlocked by appropriate auxiliary means from the opposite side of the door.

It is a general object of this invention to provide a lock of this class which is simple and economical of construction and simple and economical to install.

With these and other objects in view, as will appear hereinafter, I have devised a door lock having certain novel features of construction, combination, and arrangement of parts and portions, as will be hereinafter described in detail and particularly set forth in the appended claims, reference being had to the accompanying drawings, and to the characters of reference thereon, 55

which form a part of this application, in which:

Fig. 1 is a horizontal longitudinal sectional view of my lock, in its preferred form of construction, installed in a door, showing the latch bolt mechanism in longitudinal section, and also showing some of the parts unsectioned to facilitate the illustration;

Fig. 2 is a partial longitudinal section thereof, taken through 2—2 of Fig. 1;

Fig. 3 is a partial end and partial sectional view of the outside knob of my lock, with the view taken through 3—3 of Fig. 2;

Fig. 4 and 5 are sectional views thereof, taken respectively through 4—4 and 5—5 of Fig. 2;

Fig. 6 is an inside view of the locking slide; Fig. 7 is a sectional view thereof, taken through 7—7 of Fig. 1;

Fig. 8 is an end view of the inside knob, taken at 8—8 of Fig. 2;

Figs. 9 and 10 are sectional views thereof, taken through 9—9 and 10—10 of Fig. 1;

Fig. 9a is an enlarged fragmentary sectional view showing the inner knob and the button for actuating the inner end of the locking spindle.

Fig. 11 is a longitudinal section of the latch bolt mechanism;

Fig. 12 is an outer end view thereof;

Figs. 13, 14, and 15 are sections taken respectively through 13—13, 14—14, and 15—15 of Fig. 11.

Fig. 16 is a view similar to that of Fig. 11 but showing the bolt in a retracted position;

Fig. 17 is a fragmentary view of the inner end of the latch bolt mechanism, substantially as shown in Fig. 11, but showing the bolt actuating means in a slightly modified form of construction;

Fig. 18 is a sectional view thereof, taken through 18—18 of Fig. 17;

Fig. 19 is a fragmentary view of my lock in a slightly modified form of construction, for use on inside doors;

Fig. 20 is an end view of the normally outer knob, taken at 20—20 of Fig. 19; and,

Fig. 21 is a sectional view thereof, taken through 21—21 of Fig. 19.

My latch bolt mechanism is enclosed in a housing 1 which is of substantially circular cross-section except for slightly flattened opposite sides, as shown in Figs. 13, 14, and 15, so that it may be easily inserted into a drilled hole in the edge of the door. In the recess of the housing are reciprocally mounted a latch bolt 2 and a latch bolt actuating member 3, the former at the outer end and the latter at the inner end

of the housing. The bolt has a cut-out portion 2^a at its inner end, providing at one side a portion 2^b which extends backwardly into a cut-out portion 3^a at one side of the actuating member. Thus, the two members overlap each other. Within the cut-out portion 2^a is located a compression spring 4 which normally separates the bolt and actuating member, forcing the bolt outwardly to its normal latching position. The spring is of relatively large diameter and relatively long, extending into a recess of the bolt, thus insuring greater resiliency and longer life of the spring.

At one side of the cut-out portion of the actuating member is an outward extension 3^b, in which is provided a longitudinal slot 3^c, in which is located the hub of a rocker 5. The rocker is pivoted on a pin 6, supported in the opposite flat walls of the housing. This rocker has diametrically opposite arms, namely a short arm 5^a extending into a transverse notch 3^d at the outer side of the longitudinal slot, and a longer arm 5^b extending into a transverse notch 2^c in the backward projection 2^b of the bolt. The longitudinal slot permits the actuating member 3 to be reciprocated freely.

As the actuating member 3 is forced outwardly, as will be described hereafter, the shoulder, forming the inner side of the notch 3^d, engages the short arm of the rocker 5 and forces the end of the longer arm 5^b, which is bent backwardly slightly, against a corresponding shoulder forming the inner side of the notch 2^c, withdrawing or retracting the bolt.

In the door is provided the usual latch operating spindle 11. The cross-section of the spindle, in this instance, is semi-circular, with the flat side outwardly, and the opposite edges engaging the inner end of the actuating member 3, as shown. At the axial portion of the operating spindle is provided a locking spindle 12, which is preferably a rod of relatively small diameter and is rotatable with respect to the operating spindle. To allow clearance for the locking spindle 12, the inner end of the actuating member 3 has a transverse notch or is bifurcated, as shown in Fig. 11. It may then be said that the flat portions of the operating spindle 11, at the opposite sides of the locking spindle or rod 12, engage the inner ends of the furcations of the actuating member, as shown in Figs. 11 and 16.

In the lock shown in Figs. 1 and 2, I have provided an outside knob 21 and an inside knob 22. In the outer end of the outside knob is a recess 21^a in which is pressed a cylinder lock which consists of a cylinder 23 and a plug 24, which are provided with the usual tumbler pins 25. The cylinder 23 is made of a soft metal core 23^a and having an outer hard metallic face 23^b. The soft metal member 23^a is pressed into the recess 21^a of the soft metallic core 21^b in the outer knob and is thereby frictionally held in position. The plug 24 may be held in place by a pin 26 at its inner end.

The spindle 11 has a collar 11^a at its outer end which engages a shoulder 21^c in the outer knob 21, and thus locates the spindle in this knob. The inner end of the spindle extends into the axial portion of the inner knob and is secured in place by a screw 27. The knobs 21 and 22 may have shoulders 21^d and 22^a which may extend into recesses in escutcheon plates 28, 75

at the opposite sides of the door for preventing endwise movement of the spindle.

Or, if desired, the inner ends of the hubs of the knobs 21 and 22 may engage the opposite sides of the bolt housing 1 to prevent endwise movement of the knobs. In this event, the escutcheon plates 28 may have larger holes to receive the hubs of the knobs. Such structure is shown in Fig. 19.

10 The locking spindle 12 is provided at its outer end with a bifurcated portion, which may consist of a longitudinal projection 12^a and an offset lug 12^b, between which the inner end of the key 29 may be inserted for rotating the locking spindle about its axis, that is, when the cylinder lock allows the key to be turned.

15 The locking spindle has a radial lug 12^c which rides in an arcuate groove 11^b in the operating spindle to allow the locking spindle to be rotated but prevent axial movement of the latter. The inner side of the operating spindle, between the arcuate groove 11^b and the latch housing 1, is provided with a longitudinal recess 11^c in which is located an outwardly bowed leaf spring 30.

20 25 The intermediate portion of the leaf spring is urged against either one of two flat sides 12^d and 12^e on the locking spindle, resiliently to hold the locking spindle in either an unlocked or locked position.

30 35 The locking spindle is provided with a second radial lug 12^f which extends into a spiral groove 31^a of a locking slide 31. This locking slide is located at the diametrically opposite side of the locking spindle or rod from the actuating spindle, and is slidable against the flat sides of the latter within the hub of the outer knob. The inner end of the slide has a longitudinally extending locking projection 31^b which is adapted to extend into a transverse recess 3^e spaced inwardly

40 45 from the recess or bifurcation at the inner end of the actuating member, but which is separated therefrom by a suitable wall or lugs 3^f, as shown best in Figs. 11 and 16.

50 Thus, when the locking spindle is rotated, the lug 12^c prevents longitudinal movement of the locking spindle, but the lug 12^f, operating in the spiral groove 31^a, forces the locking slide 31 to move longitudinally. When the key 29 is turned counter-clockwise, the locking projection 31^b enters the locking recess 3^e of the actuating member, preventing the latter from being forced outwardly by the operating spindle, and thereby also preventing the operating spindle from being rotated.

55 60 65 70 At the axial portion of the inner knob is axially rotatable a button 41, the outer end being suitably shaped to permit ready rotation. This button is preferably made from a soft metal. The inner end of this button has a square shank 41^a which enters a square recess 12^g at the inner end of the locking spindle or rod. Intermediate the outer end of the button and the square shank is an enlarged collar 41^b provided with longitudinal ribs 41^c. This collar is adapted to be forced through a central hole 22^b at the outer end of the knob, slightly distorting the longitudinal ribs 41^c but preventing the ready removal of the button after being forced into position.

75 80 85 This button is adapted to rotate the locking spindle from the inside, as in the case of the key 29, from the outside, for forcing the locking lug 31^b in interlocking relation with the latch actuating member.

In the modified structure of my lock, shown

in Figs. 19, 20, and 21, only a locking means is provided at one of the knobs. This lock is intended for use in such cases in which the door is to be locked from one side only, such as in the case of a bathroom lock. This locking means is shown as consisting only of a button 41, as described above. However, it will be noted that in order to provide some means of unlocking the door from the opposite side, as required by some municipal ordinances, I have provided an opening 42^a at the outer side of the axial portion of the knob 42. Into the opening 42^a may be inserted a screw driver, or other suitable instrument, for engaging the outer end of the locking spindle 43. In this instance, the outer end is shown as provided with a screw slot 43^a whereby the spindle may be easily rotated for unlocking the door.

A feature of this modification consists in the pressing of one end of the spindle 45 into the hub of the inner knob 44. To facilitate such operation and retention of said one end of the spindle, I have provided longitudinal ribs 45^a.

A feature of all of the structures shown is the provision of the spindle receiving bore in the hub of such shape that relative rotatable movement is prevented by one with respect to the other. Such rotation preventing means may consist of oppositely located lugs in the respective hubs, as indicated by 44^a in Fig. 21.

In the modification shown in Figs. 17 and 18, I have shown a square spindle 51 for operating the actuating member 3. However, this square spindle is inserted through a longitudinal hole 52^a, of square cross-section, in an operating collar 52, which is rotatably mounted at the inner end of the housing 1. This collar has a cut-out portion intermediate its ends, forming separate faces or lugs 52^b which engage the inner ends of the aforementioned furcations, designated 3^c at the inner end of the actuating member 3. The bifurcation or recess at the inner end of the actuating member permits rotation of the spindle 51.

Though I have shown and described a particular construction, combination, and arrangement of parts and portions, and certain modifications thereof, I do not wish to be limited to the same, but desire to include in the scope of my invention the construction, combination, and arrangement substantially as set forth in the appended claims.

I claim:

1. In a lock of the class described, a housing, a latch actuating member in the housing for operating a latch, the latch actuating member having a bifurcated inner end, a latch operating spindle of substantially semi-cylindrical cross-section rotatably mounted in and extending transversely through the housing, a locking spindle at the axial portion of the latch operating spindle, the former being rotatable with respect to the latter, one side of the operating spindle being flat and each of the portions thereof at the opposite sides of the locking spindle engaging one of the ends of the furcations of the actuating member, means for rotating the spindle, and locking means for operating the locking spindle and causing the latter to interlock with the actuating member.

2. In a lock of the class described, a latch housing having latch means therein, a rotatable operating spindle for retracting the latch means, said operating spindle being of substantially semi-cylindrical cross-section, a locking rod lo-

cated at the axial portion of the spindle, the spindle and rod having means for holding the rod against endwise movement but permitting relative rotative movement of the rod and the spindle, a locking slide at the side of the rod opposite the spindle, said slide being longitudinally shiftable but rotatably fixed with respect to the spindle, and a pin and spiral groove means in association with the slide and locking rod for forcing the slide longitudinally in interlocked relation with the latch means when the rod is rotated.

3. In a lock of the class described, a latch mechanism, means for operating the latch mechanism, and a locking rod in association with the operating means for locking the latch mechanism, one end of the rod having a longitudinal extension and also a lateral projection spaced laterally from the extension, the space between the extension and the projection adapted to receive a key through the operating means for rotating the rod.

4. In a lock of the class described, a latch mechanism, means for operating the latch mechanism, and a locking rod in association with the operating means for locking the latch mechanism, said operating means having a hole in alignment with the adjacent end of the locking rod, and the latter end of the locking rod being transversely slotted for receiving a flat instrument through said hole to facilitate the rotation of the rod.

5. In a lock of the class described, a latch mechanism, an operating spindle for the latch mechanism, said spindle being of substantially semi-cylindrical cross-section and an operating knob having a hub and a longitudinal recess in the hub for receiving one end of the spindle, the recess of the hub having opposed lugs for engaging the lateral portions of the flat side of the spindle, to prevent mutual rotation of the knob and spindle.

6. In a lock of the class described, a lock operating means, a locking rod mounted in the operating means for locking the lock, and a locking button at the outer end of the operating means, said locking button and the adjacent end of the locking rod having a sliding connection of polygonal cross-section whereby the locking rod is rotated with the rotation of the button, said button having a collar intermediate its inner and outer ends and longitudinal ridges at the periphery of the collar, said operating means having a hole in alignment with the locking rod through which the inner end and collar of the button are adapted to be inserted for interlocking engagement with the locking rod, said ridges being slightly distorted when the collar is forced through said hole, thereby preventing ready withdrawal of the button.

7. In a lock of the class described, a latch housing having latch means therein, a rotatable operating spindle for retracting the latch means, said operating spindle being of substantially semi-cylindrical cross-section, a locking rod located at the axial portion of the spindle, the spindle and rod moving means for holding the rod against endwise movement but permitting relative rotative movement of the rod and the spindle, a locking slide at the side of the rod opposite the spindle, said slide being longitudinally shiftable but rotatably fixed with respect to the spindle, and means in association with the slide and locking rod for forcing the slide longitudinally in interlocked

relation with the latch means when the rod is rotated.

8. In a lock of the class described, a lock operating means, a locking rod movably mounted in the operating means, and a readily-distortable soft-metal locking button at the outer end of the operating means, said locking button being operatively connected to the adjacent end of the rod, said operating means having a hole in alignment with the rod through which the inner end of the button is adapted to be inserted for operative engagement with the rod, said button having intermediate its ends a channel portion which is positioned opposite and rotatable in said hole, the portion of the button outwardly from the channel portion being substantially larger than the hole and the portion thereof inwardly from the channel portion being enlarged, the latter portion being slightly distorted when forced through the hole, thereby preventing ready withdrawal of the button therefrom.

9. In a lock of the class described, a lock operating means, a locking rod movably mounted in the operating means, and a readily-distortable soft-metal locking button at the outer end of the operating means, said locking button being operatively connected to the adjacent end of the rod, said button having a collar intermediate its ends and longitudinal ridges at the periphery of the collar, said operating means having a hole in alignment with the rod through which the inner end and collar of the button are adapted to be inserted for operative connection with the operating rod, said ridges being slightly distorted when the collar is forced through said hole, there- 35

by preventing ready withdrawal of the button therefrom.

10. In a lock of the class described, an operating spindle means for the lock, a knob for one end of the spindle means, the outer end of the knob having an opening, and a lock means for the operating spindle, said lock means having a readily-distortable soft-metal body extending through and rotatable within the said opening and operatively connected to the spindle means, the portion of the body inwardly of the opening having substantially longitudinal ridges tapered inwardly, the outer ends of the ridges being of such size and so positioned as to be slightly distorted when the same is forced through said hole, thereby preventing ready withdrawal of the end of the body having the ridges, through the opening of the knob.

11. In a lock of the class described, an operating spindle means for the lock, a knob for one end of the spindle means, the outer end of the knob having an opening, and a lock means for operating the spindle means, said lock means having a readily-distortable soft-metal body extending through and rotatable within the said opening and operatively connected to the spindle means, the portion of the body at the inner end of the opening being enlarged and longitudinally ridged, the ridges being tapered inwardly, the enlarged and ridged portion of the body being of such size and so positioned as to prevent withdrawal of the enlarged and ridged portion of the body from the knob through the opening.

JAMES HILLGREN.
